UNITED STATES PATENT OFFICE.

JACOB T. MOYER, OF QUAKERTOWN, PENNSYLVANIA.

ELEVATOR-BRAKE.

1,201,749.

Specification of Letters Patent.

Patented Oct. 17, 1916.

Application filed December 28, 1915. Serial No. 69,073.

To all whom it may concern:

Be it known that I, JACOB T. MOYER, a citizen of the United States, residing at Quakertown, in the county of Bucks and 5 State of Pennsylvania, have invented certain new and useful Improvements in Elevator-Brakes, of which the following is a specification.

This invention relates to an improved 10 brake which is to be connected with an elevator and which will operate automatically when the lifting cable breaks thus stopping the car and preventing it from falling down the elevator shaft.

15 This brake is so constructed that when the car is in working order, the gripping bars will be held out of engagement with the rack and is further so constructed that when the cable breaks, springs forming part 20 of the improved structure will move a wedging block downwardly thus moving the gripping bars outwardly to engage the teeth of the rack bars.

This device is further so constructed that 25 the movement of the wedging blocks in one direction will be limited thus preventing the wedging block from being drawn out of place when the car is in use and is further so constructed that movement of the 30 gripping bars will be guided and the bars thus caused to be moved to the proper position for engaging the teeth of the rack bars.

This improved device is illustrated in the accompanying drawings, wherein:—

35 Figure 1 is a view in elevation showing the brake in the inoperative position. Fig. 2 is a view in elevation showing the brake in the operative position. Fig. 3 is a top plan view of the brake. Fig. 4 is a trans- 40 verse sectional view taken along the line 4—4 of Fig. 2. Fig. 5 is a bottom plan view of the brake. Fig. 6 is a sectional view taken along the line 6—6 of Fig. 5, the wedging block being shown in elevation.

45 The elevator car with which this brake is to be connected is provided with arms 10 which extend above the car and carry side plates 11 extending upon opposite sides of the tracks 12. These tracks 12 are provided 50 with teeth as shown in Figs. 2 and 3 thus providing rack bars 13 which will be engaged by the brake mechanism and prevent the car from falling down the elevator shaft when the cable 14 breaks.

55 The brake includes a frame having side bars or walls 15 connected with the arms 10

and a bottom 16 positioned between the side walls 15 and braced by brackets 17. The flooring 16 is provided with a tapered passageway 18 through which the wedge 19 passes, the wedge being provided with side ribs 20 fitting into grooves 21 formed in the side walls 15. Therefore the wedge will be prevented from moving longitudinally between the side walls. Side plates 22 are secured to the side walls 15 by means of screws or other fasteners and are provided with slots 23 which receive tongues 24 extending from the plate 25 secured to the end of the wedge 19. This plate 25 limits the upward 65 movement of the wedge and prevents the wedge from being drawn entirely out of the passageway 18 when the car is in operation. Springs 26 are secured to the plate and when the car is in operation these springs are extended as shown in Fig. 1. When the cable 70 breaks, the springs will move to the position shown in Fig. 2 and draw the wedging block downwardly. The gripping bars 27 which are to engage the rack bars 13 rest upon 75 the bottom or flooring 16 and are guided in their sliding movement by the guiding blocks 28, which blocks are secured between the side walls 15 and are provided with openings 29 through which the gripping bars pass and with slots 30 through which 80 rods 31 pass. These rods 31 are pivotally connected with the gripping bars and with the upper end portion of the wedging block 85 as shown at 32 and 33 and it will thus be 90 readily seen that when the wedging block moves, the gripping bars will be moved longitudinally into or out of engagement with the rack bars. Therefore when the cable 95 breaks, the gripping bars will engage the rack teeth.

What is claimed is:—

1. A brake including carrying bars, a housing carried by said bars and including side walls and a bottom wall positioned between the side walls and provided with a tapering opening intermediate its length, guiding blocks positioned in said housing between said side walls, gripping bars resting upon the bottom of said housing and 100 passing through said guiding blocks, a wedge slidably mounted in the opening of said flooring, links pivotally connected with said wedge and pivotally connected with said gripping bars, guide plates secured to 105 the side walls of said housing and provided with slots, a plate secured to said wedge and 110

provided with tongues fitting into said slots, and springs secured to said plate and yieldably holding the wedge in a position to retain said gripping bars extended.

2. A brake of the character described including a housing having side walls and a flooring provided with a tapered opening, a wedge slidably mounted in the tapered opening, side plates secured to said housing and provided with slots, an abutment plate secured to said wedge and extending into the slots of said side plates, gripping bars slidably mounted in said housing, links connecting said gripping bars with said wedge, and spring elements secured to said abutment plate and engaging said housing.

3. A brake of the character described in-

cluding a housing having a flooring provided with an opening, actuating means slidably mounted in the opening, guiding plates secured to said housing, an abutment plate secured to said actuating means and slidably engaging said guiding plates, gripping bars slidably mounted in said housing, links connecting said gripping bars with said actuating means, and spring elements secured to said abutment plate and engaging said housing.

In testimony whereof I affix my signature in presence of two witnesses.

JACOB T. MOYER.
